UNITED STATES PATENT OFFICE.

OTTO WILLIAM LUTZ, OF PETALUMA, CALIFORNIA.

INCUBATOR.

No. 823,182.

Specification of Letters Patent.

Patented June 12, 1906.

Application filed January 2, 1906. Serial No. 294,165.

To all whom it may concern:

Be it known that I, OTTO WILLIAM LUTZ, a citizen of the United States, residing at Petaluma, in the county of Sonoma and State of California, have invented new and useful Improvements in Incubators, of which the following is a specification.

My invention relates to poultry-incubators. Its object is to provide a simple, practical, and automatically-governed incubator, and especially one of large size, in which the egg-chambers shall be heated by direct rather than by radiated heat and to provide certain improvements in the arrangement for quickly mechanically heating, distributing, and vitalizing the air, whereby a healthier condition will prevail than under ordinary present methods.

The invention consists of the parts and the construction and the combination of parts, as hereinafter more fully described and claimed, having reference to the accompanying drawings, in which—

Figure 1 is a longitudinal section through my poultry-incubator. Fig. 2 is a cross-section of the same. Fig. 3 is a horizontal sectional view through the apparatus, taken between the air-tank and the fabric 19'. Fig. 4 is a perspective of a part of the apparatus, showing the hinging of the parts 3 and 9 and the means for supporting the egg-trays.

A represents a box of suitable size, shape, and material. It is possible to make very large machines and to operate them successively by reason of my special construction, which I shall now set forth. This box is provided with a suitably-hinged lid 2 and has suitable openings at its two sides for the insertion and removal of the egg-trays and for the purpose of giving access to the box for cleaning and other purposes. These side openings are closed by the hinged doors 3, of which there may be one or more on each side of the machine. The ends of the box are provided with suitable ventilating-flues 4, open to the atmosphere at the top and to the interior of the box at the bottom. The flues may be closed by slides 4'.

The egg-trays are supported a few inches above the bottom of the box on the removable slideways 5. These slideways are shown as consisting of flat boards extending about one-half the width of the box and having downwardly-extending projections 6 at one end to support the rear end of the slide on the box and with the front end of the slides

notched, as at 7, to fit over the projections 8 on a front board 9, which runs the entire length of the box. If desired, this front board may be hinged to the bottom of the box, as at 10, so that with the doors 3 open downwardly it is possible to swing the board 9 outwardly on its hinges and by removing the several slides leave the bottom of the box entirely open and unobstructed for cleaning purposes. This accessibility to the box is of great importance, since it enables a most thorough cleaning of the box after each hatch or at any other time, which is very important in the successful raising of young chicks.

A set of slideways is adapted to be inserted from each side of the machine, and a corresponding set of egg-trays may be inserted from each side of the machine, each slide being designed to support a side of two trays. The trays do not extend the full length of the slides for the purpose of providing a suitable space at the front end of the trays to allow the little chicks after hatching to climb out of a tray and drop down into the space beneath the trays. In order to prevent the chicks after hatching from climbing from one tray to another, a screen-section, as 11, supported in suitable longitudinal channels in the slideways 5, may be slipped in between the trays.

12 is an inclosed heating-tank arranged at a suitable distance above the trays and extending nearly the length and breadth of the incubator-box. This tank is suitably supported in the incubator-box and is adapted to receive the heat from the source of heat-supply and also a limited quantity of fresh air and after suitably mixing the heated vapors and fresh air and distributing the same throughout the tank to deliver the heated and tempered mixture into the egg-chambers. This heating, mixing, and distribution is here shown as effected by the following means: I prefer to use gas for heating purposes, and I may use one or more suitable gas-burners, as 13, according to the size of the apparatus. As I am here illustrating a large size apparatus I have shown two burners arranged one on each side of the middle of the apparatus. These burners 13 are arranged beneath the incubator-box and are adapted to direct their heat up through a tube 14, which communicates directly with the interior of the tank 12. The tube 14 is surrounded by a second tube or cylinder 15,

which is open at the bottom to the atmosphere and at the top to the interior of the egg-chamber. Beneath the tank 12 a second tube or flue 16 is arranged around and 5 out of contact with the tube 15 and is also in communication with the outer atmosphere and with the egg-chamber. The object of the two tubes 15 and 16 is to supply hot 10 fresh air direct to the chamber and also a limited quantity of cold fresh air, mixing the 15 hot and cold air at the point of discharge into the egg-chamber. In order to create a circulation of heat in the tank 12 and to insure an equable distribution of the heat to all corners thereof, there are provided the tubes or 20 flues 17 at each end of the tank, which extend outwardly of the ends of the incubator and which open to the atmosphere. The heat from the burners after being thoroughly mixed and distributed in the air-chamber inclosed by tank 12 is discharged 25 downwardly into the egg-chamber through a short section of tubing 18 and in opposition to an up-rushing current of cold air entering through a flue 19, which is open to the atmosphere beneath the incubator and is open to the egg-chamber at the top. The hot air from the tank is thus vitalized by the fresh air entering through the flue 19, so that in 30 practice it is found that this heated and vitalized air and the air which enters through the tubes 15, 16, 18, and 19, preserves a healthy atmosphere continually in the egg-chamber, suitable means being employed to maintain a uniform 35 temperature. In order to effect an equable distribution of the air entering through the several tubes 15, 16, 18, and 19, I may employ a transversely-extending partition of cheese-cloth 19' or the like, (shown by dotted 40 lines in Figs 1. and 2 and shown more fully by full lines in Fig. 3,) arranged just below the air-inlets to the egg-chamber. This cheese-cloth will serve to check air-currents and at the same time will offer no substantial 45 resistance to the passage of the air into the presence of the eggs and chicks.

Any suitable form of temperature and heat regulating means may be employed. In the present instance I have shown a well-known 50 form of regulator in which the gas or the burner enters a regulator 20 through a pipe 21 and discharges through a pipe 22 to burner 13, the flow of the gas to the burner being controlled by a valve 23, which is operated from the thermostat 24, disposed in 55 the egg-chamber. As the heat in the egg-chamber increases to an undesired point the disk of the thermostat 24 expands, operating through the rod 25 and lever 26 to close more or less the valve 23, thereby decreasing the 60 gas-pressure at the burner and allowing a proportionately greater amount of cold air to enter the egg-chamber. As the temperature becomes reduced in the egg-chamber the 65 thermostat contracts and opens up the valve

23, thereby increasing the flame at the burner. If desired, a moisture-pan 27 may be arranged on top of the tank 12 and adapted to be filled through a valved pipe 28, carried by the lid 2 of the incubator-box. The 70 pan 27 may be provided with an outlet 29, extending off to one side and discharging exterior of the incubator-box. This arrangement of the moisture-pan is convenient, since it enables it to be filled without having to 75 open the apparatus, as is usual in most incubators, since this opening of the apparatus during incubation is not conducive to best results.

It will be observed that while a certain 80 amount of radiated heat will be given off by the air-tank 12 the main supply of heat to the gas is direct heat, or rather the heating is chiefly done by the admission of hot fresh air direct into the egg-chamber. This has 85 been found to be conducive to a greater proportion of sound healthy chicks than where heating is done purely by means of water or steam pipes or the like, and, furthermore, a saving of both heat and fuel is effected. 90 instead of letting out the heat from the egg-chamber, as is usual when the temperature gets too hot. Whenever the chamber gets too hot, the heat is here simply cut off or decreased and is not increased again until the 95 chamber is cooled sufficiently.

The arrangement of the doors 3 and of the hinged front supports 9 for the slides 5 and the making the slides 5 removable, enable the incubator to be opened up and cleaned with 100 the utmost facility and thoroughness. The vertical end flues 4 operate to maintain the necessary circulation in the incubator and serve to remove the coldest and impurest air from the bottom of the chamber, leaving 105 fresh hot air above. By having the trays readily removable from each side of the incubator and by having them extend only half the width of the incubator-box it permits the 110 trays to be turned and to have their positions changed from time to time, so that all the eggs in all the trays will be subjected to an equal heat and all hatch at once. In machines where the trays extend clear across the incubator-box the eggs in the middle, 115 which are subjected to the most heat, hatch out first.

Having thus described my invention, what I claim, and desire to secure by Letters Patent, is—

1. An incubator comprising a box having a side opening, a door for said side opening, removable slideways insertible through the opening, said slideways having suitable rear end supports, a hinged bar opening outwardly 125 to support the front end of said slideways, trays on said slideways, and means for heating the interior of the box.

2. An incubator comprising a box inclosing an egg-chamber, an air-tank within said box, 130

means for delivering hot air into the tank, and means for delivering the heated air in the tank into the egg-chamber and for mixing the same with cold air from outside the incubator.

3. In an incubator, a box inclosing an egg-chamber, a source of heat-supply, and means for circulating hot air directly through the egg-chamber.

4. In an incubator, a box inclosing an egg-chamber, an air-tank in the chamber, a source of heat-supply, means for delivering heat directly into the air-tank, means for discharging the heat from the tank into the egg-chamber and for admitting fresh air into the egg-chamber and mixing it with the heated air from the tank.

5. In an incubator, a box inclosing an egg-chamber, a tank in the box, a source of heat-supply, communications between said source of supply and the interior of the tank, said tank having a downwardly-extending outlet, said box having an air-inlet into which said hot-air outlet discharges and wherein the hot and cold air is mixed, said heated mixture having a discharge into the egg-chamber.

6. In an incubator, a box inclosing an egg-chamber, an air-tank in the chamber, pipes extending from the ends of the tank exterior to the box, a heating-pipe entering the tank, means for heating the air admitted through said pipe, air-tubes surrounding said pipe and open to the atmosphere and also to the interior of the chamber, and admitting hot air to the chamber, and means for passing the hot air in the tank into the egg-chamber.

7. In an incubator, a box inclosing an egg-chamber, an air-tank in the chamber, pipes extending from the ends of the tank exterior to the box, a heating-pipe entering the tank, means for heating the air admitted through said pipe, air-tubes surrounding said pipe and open to the atmosphere and also to the interior of the chamber and admitting hot air to the chamber, means for passing the hot air in the tank to the egg-chamber, and means for mixing cold air with said hot air

from the tank before its admission to the egg-chamber.

8. An incubator comprising a box inclosing an egg-chamber, a hot-air tank therein, a pipe entering said tank, means for heating the air admitted through said pipe into the tank, an air-pipe surrounding said heating pipe and inclosing a separate air-passage, said air-pipe open to the atmosphere and to the egg-chamber and adapted to deliver fresh air to the egg-chamber, said tank having an outlet and hot-air connections with the egg-chamber.

9. An incubator comprising a box inclosing an egg-chamber, a hot-air tank therein, a pipe entering said tank, means for admitting a heating medium through said pipe into the tank, an air-pipe surrounding said heating pipe and inclosing a separate air-passage, said air-pipe open to the atmosphere and to the egg-chamber and adapted to deliver fresh air to the egg-chamber, said tank having an outlet to the egg-chamber, means for controlling the amount of heat according to the temperature of the egg-chamber, and the ends of the box having vertical flues communicating with the outer atmosphere and with the bottom of the egg-chamber.

10. An incubator comprising a box inclosing an egg-chamber, an air-tank in the box, removable slideways in the egg-chamber and removable trays supported on said slideways, removable partitions between the trays, means for admitting hot air to the air-tank, and means for mixing cold air with the hot air from the tank and for discharging the heated mixture into the egg-chamber, a moisture-pan, and means permitting the filling and emptying of the pan from the outside of the box and without opening the latter.

In testimony whereof I have hereunto set my hand in presence of two subscribing witnesses.

OTTO WILLIAM LUTZ.
